Primary Examiner — Cathy A MacCormac

(57) **CLAIM**

I claim the ornamental design for the pet toy, as shown and described.

DESCRIPTION

FIG. 1 is a perspective view of the invention, showing my new design;

FIG. 2 is a top plan view thereof; the bottom plan view being identical;

FIG. 3 is a side elevational view thereof; the opposite side being identical; and,

FIG. 4 is an end view thereof; the opposite end view being identical.
